United States Patent Office

Des. 185,289
Patented May 26, 1959

185,289

OVERSHOE

Joseph J. Kadlec, La Crescenta, Calif.

Application February 24, 1958, Serial No. 49,759

Term of patent 14 years

(Cl. D7—4)

Fig. 1 is a perspective view showing the front and left side of an overshoe embodying my new design.

Fig. 2 is a sectional view taken on the line 2—2 of Fig. 1.

Fig. 3 is a side perspective view of the overshoe shown in Fig. 1.

I claim:

The ornamental design for an overshoe, substantially as shown.
